UNITED STATES PATENT OFFICE.

SOLOMON WILE, OF ROCHESTER, NEW YORK.

SLICING MACHINE.

Application filed July 30, 1924. Serial No. 728,993.

To all whom it may concern:

Be it known that I, SOLOMON WILE, a citizen of the United States, and resident of Rochester, in the county of Monroe and State of New York, have invented certain new and useful Improvements in Slicing Machines, of which the following is a specification.

The present invention relates to slicing machines and more particularly to the type in which a cutter is mounted on a main frame and a carriage reciprocates back and forth past the cutting edge of the cutter and carries a meat table which is advanced toward the plane of operation of the cutter upon each back and forth movement of the carrier. An object of this invention is to provide an improved locking means which will lock the meat table against movement either in a retrograde direction or in an advancing direction, while, at the same time, will permit the advancing of the table through the medium of a step by step advancing mechanism.

To this and other ends, the invention consists of certain parts and combinations of parts, all of which will be hereinafter described; the novel features being pointed out in the appended claims.

In the drawings:

Fig. 1 is a plan view of a slicing machine constructed in accordance with this invention;

Fig. 2 is an enlarged plan view of the table and carriage broken away to illustrate the operating parts;

Fig. 3 is a view similar to Fig. 2, showing the locking device out of locking relation with the toothed member;

Fig. 4 is a section on the line 4—4, Fig. 3; and

Fig. 5 is a section on the line 5—5, Fig. 3.

In the illustrated embodiment, 1 indicates the main frame of the machine which has a rotary cutter 2 mounted to turn thereon through the medium of a crank disk, this crank disk being also connected to a carriage 4 for imparting to the carriage a reciprocating or back and forth movement past the edge of the cutter. On the carriage 2 is a meat table 5 which through guides 6 is movable transversely of the line of movement of the carriage 4 toward and from the plane of operation of the cutter 2, all of which is not fully shown herein but is old in the prior art. A material clamp 7 of any

suitable construction is arranged on the meat table 5 to secure the material against movement on the table.

Movement of the table 5 on the carriage 4 is effected preferably through a rack bar 8, in this instance, pivoted at 9 to the underside of the table 5 and extending beyond one side of the table to provide a finger piece 10 by which the rack 8 may be moved on its pivot 9, a latch 11 holding the rack normally in operative position. Cooperating with this rack is a pinion 12 which is rigidly secured to a stub shaft 13 mounted to turn in a strap 14 which is by bolts 15 secured to the underside of the carriage 4, the carriage having an opening 16 through which the shaft 13 extends in order that the pinion 12 may lie above the carriage 4 and cooperate with the rack 8. Rigidly secured to the shaft 13 is a ratchet wheel or toothed member 17. Movement of this ratchet or toothed member 17 may be effected by a swinging member 18 mounted to turn between its ends on the shaft 13 and having on one side of its pivot a spring 19 connected thereto at one end, the other end of the spring being anchored at 20 to the underside of the carriage 4. The spring normally holds the member 18 against the stop 24 on the carriage 4. On the opposite side of the pivot of the swinging member 18 the latter carries an advancing pawl 21 which is pivoted at 22 to said member 18 and is held normally in engagement with the toothed member 17 by a spring 23. Arranged on the main frame 1 is a stop or abutment 24^a which, as the carriage 4 approaches the extreme end of its return movement before its movement in advancing toward the knife to produce the cutting, is engaged by the lug 18^a the swinging member 18 and shifts the latter on its pivot to cause the advancing pawl 21 to shift the toothed or ratchet wheel 17 and turn the gear 12, thereby shifting the table 5 one step. Movement of the table in the opposite direction may be effected by releasing the rack bar 8 from the latch 11 so that the rack bar may be swung on its pivot 9 in order to be disengaged from the gear 12, thereby permitting the table 5 to be moved away from the knife or toward the knife by a quick movement.

The locking mechanism embodies preferably a toothed member 25, in this instance, in the form of a disk or wheel secured to the shaft 13 to turn therewith. This toothed

member has the notches between its teeth V shaped and in these notches the V shaped end 26 of a locking detent 27 is adapted to engage. This locking detent, in this instance, is slidably mounted in guides 28 and is moved toward the toothed member 25 by a coil spring 29 secured at one end at 30 to the detent and the other end at 31 to one of the guides 28. This detent is operated away 5 from the locking member just prior to the time that the carriage 5 is shifted through the advancing pawl 21 and immediately re-engages the toothed member 25 after the shifting. This result, in this instance, is effected by shifting the pawl 32 pivoted between its ends at 33 to a swinging member 34, that is, in turn, pivoted at 35 to the under side of the carriage 4. The shifting pawl 32 has a nose 36 which is adapted to enter 10 a notch 37 in the detent 27 to engage one wall of the notch in order to shift the detent 27 away from the toothed member 25. The detent 32 also has a bevelled portion 38 which is adapted to cooperate with a fixed 15 abutment 39 after the shifting detent 32 has been moved a certain distance.

As the carriage 4 approaches the end of its return movement and before the swinging member 18 engages the stop or abutment 24, the swinging member 34 strikes an inclined abutting surface 40 on the main frame 1 and shifts the swinging member 34 on its pivot 35, thereby causing the nose 36 of the shifting pawl 32 to shift the detent 27 out of engagement with the toothed member 25. Thereafter the swinging member 18 engages the abutment 24 and shifts the advancing pawl 21 so as to advance the carriage 5 toward the knife. While this advancing is taking place, the swinging member 34 travels on the surface 41, so as to hold the detent 27 out of engagement with the toothed member 25, until the return movement is just about completed when the swinging member 34 engages an abutting surface 42 and is moved still further on its pivot, thus bringing the inclined surface 38 on the shifting detent 32 in engagement with the abutment 29 in such a manner as to shift the shifting pawl 32 on its pivot 33 out of engagement with the detent 27, thus freeing the detent 27 to the action of its spring 29 and permitting the nose of the detent to interlock with the toothed wheel 25. At 40 this time, the carriage has completed its return movement and the advancing pawl 21 has completed its movement so that the latter under the action of the spring 17 returns to normal position as the carriage advances again toward the knife on the cutting movement.

From the foregoing it will be seen that there has been provided a slicing machine in which there is a locking mechanism of novel construction holding the meat table

against movement on the carriage either toward the knife or cutting mechanism or away from such mechanism during the movement of the carriage back and forth past the cutting mechanism except when the table advancing mechanism is brought into operation. This result is accomplished by providing a toothed member moving with the table and having a locking detent engaging therewith, such detent holding the toothed member against movement in either of two directions and being moved out of cooperation with the toothed member just prior to the operation of the table advancing mechanism, and such detent being immediately released after the advancing movement of the table. The locking detent is preferably controlled by a means operated by a part on the frame and first shifting the locking detent away from locking position and thereafter releasing such detent to permit it to move into locking relation with the toothed member. In the illustrated embodiment, a swinging member on the carriage has a shifting detent pivotally mounted thereon and cooperating with the locking detent to shift the latter out of cooperation with the toothed member. Means also cooperates with the shifting detent to break its connection with the locking detent in order to permit the locking detent to move to locking position.

What I claim as my invention and desire to secure by Letters Patent is:

1. A slicing machine comprising a cutting mechanism, a carriage movable back and forth past the cutting mechanism, a table movable on the carriage toward and from the plane of operation of the cutting mechanism, a step by step advancing mechanism for the table, and locking mechanism for the table embodying a toothed member, a locking detent cooperating with the toothed member, and a shifting detent for the locking detent having a movement for shifting the locking detent out of locking relation with the toothed member, and a movement out of engagement with the locking detent to permit the locking detent to be reengaged with the toothed member.

2. A slicing machine comprising a cutting mechanism, a carriage movable back and forth past the cutting mechanism, a table movable on the carriage toward and from the plane of operation of the cutting mechanism, a step by step advancing mechanism for the table, and locking means for the table embodying a toothed member, a locking detent for cooperating with the toothed member, a swinging member, a movable shifting detent on the swinging member cooperating with the detent during the first part of the movement of the swinging member to shift the detent out of cooperation with the toothed member, and means co-

operating with said shifting detent during the latter part of the movement of the swinging member to effect the release of the locking member from the shifting detent to permit the locking detent to reengage with the toothed member.

3. A slicing machine comprising a cutting mechanism, a carriage movable back and forth past the cutting mechanism, a table 10 movable on the carriage toward and from the plane of operation of the cutting mechanism, a step by step advancing mechanism for the table, and locking means for the table embodying a toothed member, a detent, a spring normally moving said detent into interlocking relation with the toothed member, and a shifting detent for the locking detent moving the latter out of cooperation with the toothed member and releasing 20 the locking detent to the action of the spring after a certain time.

4. A slicing machine comprising a cutting mechanism, a carriage movable back and forth past the cutting mechanism, a table 25 movable on the carriage toward and from the plane of operation of the cutting mechanism, a step by step advancing mechanism for the table, and locking means for the table embodying a toothed member, a detent normally lying in cooperation with the toothed member to hold the table against movement, and means for effecting the shifting of the locking detent out of engagement 30 with the toothed member prior to the operation of the step by step advancing mechanism, and means for effecting the release of said locking detent to reengage the toothed member after the operation of the step by 35 advancing mechanism.

40 5. A slicing machine comprising a cutting mechanism, a carriage movable back and forth past the cutting mechanism, a table movable on the carriage toward and from the plane of operation of the cutting mechanism, a step by step advancing mechanism for the table, and locking means for holding 45 the table against movement, embodying a toothed member connected with the table, a locking detent for cooperation with the toothed member and mounted on the carriage, a spring normally moving said detent into cooperation with the toothed member, a swinging member mounted on the carriage, a shifting detent mounted on the 50 swinging member and cooperating with the locking detent to shift the latter out of cooperation with the toothed member, means engaging said shifting detent to throw it out of cooperation with the locking detent when 55 the swinging member is moved to a certain

position, and means on a part of the machine to which the carriage moves relatively having a portion for shifting the swinging member to move the locking member out of engagement with the toothed member prior to 65 the operation of the step by step advancing mechanism, a portion holding the swinging member against movement during the movement of the step by step advancing mechanism, and a portion again shifting the swinging member to cause the shifting detent to be kicked out of connection with the locking detent after the step by step advancing mechanism has shifted the table so that the locking detent may reengage the toothed 70 member to hold the table in its adjusted position.

6. A slicing machine comprising a cutting mechanism, a carriage movable back and forth past the cutting mechanism, a table 80 movable on the carriage toward and from the plane of operation of the cutting mechanism, a step by step advancing mechanism for the table, and locking mechanism for the table embodying a toothed member, a locking detent for cooperation with the toothed member, and means on the main frame of the machine for effecting the movement of the locking detent away from the toothed member, while the carriage is moving in one direction to permit the feeding of the table through the step by step advancing mechanism, and for effecting the release of said locking detent to permit the latter to engage the toothed member before 90 the carriage begins its movement in the opposite direction.

7. A slicing machine comprising a cutting mechanism, a carriage movable back and forth past the cutting mechanism, a table 100 movable on the carriage toward and from the plane of operation of the cutting mechanism, a step by step advancing mechanism for the table, and locking mechanism for the table embodying a toothed member, a locking detent for cooperation with the toothed member, and means on the main frame of the machine for effecting the movement of the detent out of cooperation with the toothed member after the carriage has 105 moved the table past the cutting mechanism on the return movement so that the step by step feeding mechanism may advance the table, and for effecting the release of said detent to cause the latter to engage the toothed member before the material on the table is again presented to the cutting mechanism.

SOLOMON WILE.
